UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

LANTERN.

Application filed March 2, 1925. Serial No. 12,483.

My invention relates to lanterns; more particularly it relates to lanterns adapted for use in connection with street and highway lighting, and to lanterns which are installed in exposed situations. My invention also relates to lanterns of the foregoing type generally known as ornamental lanterns.

Heretofore lanterns of this general type have been so constructed that whenever a portion of the glass is broken or a section of the frame, as is often the case, it has been necessary to remove the unit in order to have the repairs made. One of the objects of my invention is to provide a lantern of such construction that in the event that one of the panels or ribs is broken the unit may be readily repaired just where it is installed.

It is an object of my invention to provide an improved form of gasket of special construction and coloring and of retaining means for the glass panels. It is also an object of my invention to provide a lantern, the cost of repairing and of maintaining which is very low. It is also an object of my invention to provide other details of construction with the object of increasing the efficiency and serviceability of such lanterns.

The means for accomplishing the foregoing ends are hereinafter set forth in the claims, reference being had to the accompanying drawings, in which Fig. 1 shows the lantern in elevation and partly in section in order that the details of construction may be more easily understood. In this figure the canopy, the body and the base are readily recognizable, which base is sometimes known as the "bottom fitter". Fig. 2 shows that element of the frame of the lantern which is interposed between the canopy and body, sometimes known as the "top fitter", and also shows the cross element which supports the reflector. Fig. 3 is an enlarged section of the frame, Fig. 2, between the lines 3-3 and 3¹-3¹, Fig. 4 is a plan view taken along line 4-4 of Fig. 1. Fig. 5 is a section taken along line 5-5, Fig. 1, and 5-5, Fig. 2, showing the relation between the canopy, its hinge and the top fitter. Fig. 6 is a section along line 6-6, Fig. 1, showing the relation of one of the ribs of the frame, the gasket and two adjoining glass panes.

Referring more in detail to the drawings, it will be seen that the canopy 28 is one of usual and well known construction. This canopy is hinged in the usual way by pin 51 (see Fig. 5) to lugs 2 and 3 of the top fitter,

Fig. 2. The canopy is further provided with a latch 4, Fig. 1, which is adapted to enter the slot 5 in the lug 6 of the top fitter. By means of the thumb nut 7, the canopy may be located in a closed position.

The frame of the lantern comprises the top fitter element 8, Fig. 2, and the bottom fitter 9, between which the ribs 10, 11, 12, and so on, are interposed as shown in Fig. 1.

These ribs are removably secured to the elements 8 and 9 by any suitable means, such as the screws 13 and 14, Fig. 1. Each one of the ribs is provided with a longitudinal groove 14^a, Fig. 6, which is adapted to receive a gasket element 15, which element may be of any suitable material such as rubber. This gasket should be preferably light colored, such as white, or nearly white. This gasket is V-shaped on the inner side, as indicated in Fig. 6, and is provided with lateral flanges 16 and 17, and with a rib 18 on the outward side, which fits into the longitudinal groove of the rib. Between the ribs 10, 11, etc. and the flange 19 of the bottom fitter, I also provide a gasket element 20. When the ribs and the top and bottom fitters are secured together, it will be seen that the panels, such as 21, 22, 23, can be slipped into position. For example, the panel 23, Fig. 4, may be dropped into position between the gasket elements 24 and 15. Similarly, the pane of glass 22 can be dropped into place between the gasket elements 15 and 26. When a panel is in position, as indicated in Fig. 1, it has an upward and outward slope with respect to the axis of the unit, inasmuch as the top fitter is of larger diameter than the bottom fitter. In order to secure the glass plates in position I provide suitable spring devices some of which are secured to the bottom fitter and some to the top fitter. For example, in order to secure the panels 22 and 23 in position, Fig. 4, I provide a bifurcated spring 27 opposite the rib 10, Fig. 4. One of the prongs 29 of this spring 27 engages the pane 22 on one side of the gasket 25, whereas the other prong 30 engages the pane 23 on the other side. The screw 31 is used to secure the spring 29 to the bottom fitter. Each similar spring, such as the springs 32, 33, is similarly secured.

On the upper side of the lamp the panels are held in place by means of the adjusting screws 36 and 37, by means of which screws the pressure against the panels of glass may be regulated so as to insure a close fit

against the gaskets. These screws are preferably made of nonmetallic material such as hard fibre or hard rubber.

The top fitter is further provided with 5 a couple of members 38 and 39 located diametrically opposite, as shown in Fig. 2. Hinged between these two members 38 and 39 there is a beam A which supports the refractor or reflector element 40 of the unit. 10 This beam comprises a pair of strips 41 and 42, which are secured at one end to the link 43 and at the opposite end are notched and rest upon pin 44, which pin passes through a perforated support 45, and which latter is 15 secured to the element 39. The link 43 is provided with slotted channels 45, one on each side, 46 and 47, of the element 43. Through these channels 45 a pin 48 projects, which pin is held by the member 49, which 20 latter is secured to the projection 38, and which member 49 serves as a bearing for the pin 48. Near the central portion of the beam the reflector, or refractor, 40, is secured in place through the medium of a 25 bolt 50.

With this construction it is possible to tilt the reflector 40 about the pin 48 in order to re-lamp the unit. The arrangement is such that the strips 41 and 42 are merely 30 notched on the right hand end and merely rest on top of the pin 44 so that the whole beam A may be rotated about pin 48, and so that the slots 45 may slide over the ends of the pin 48 until the bottom of the slots 35 strikes the pin 48, and thus the reflector 40 may be raised to any desired height for clearing the lamp 52. After the unit has been re-lamped the beam A is let down into position once more, which position is indicated in Fig. 1.

It will be understood that the re-lamping operation may be carried out, if necessary, by the repairman by the use of a single hand. This is necessary sometimes inasmuch 45 as units of this type are often located on top of a pole and the person who is re-lamping needs one hand to hold him in position and has only one hand available for the purpose of re-lamping. Under these conditions he may unlatch and raise the dome 28, rotating it about the pivot 51, Fig. 5. After the dome is raised with the single hand, he may raise the beam A and rotate it about the pin 48, allowing the beam to fall back 55 and rest on the rim of the top fitter 8, whereupon he may readily remove the lamp 52 and put in a new one.

It will be seen that with a lantern of this construction it is possible to remove one 60 or more of the panels by removing one or more of the screws 37, and the corresponding springs, such as the spring 34, whereupon the panel may be tipped inward and withdrawn and a new panel substituted, where-

upon the spring 34 may be restored, and 65 the tension restored by means of the screws 37.

It will be readily seen that with a lamp of this construction it becomes practical to repair the lamp, or even repair the ribs by 70 loosening the screws 13 and 14, if one should be broken, without having to take down the unit, and at a very small trouble or expense. Furthermore, by the provision of the gaskets, such as gaskets 20, 15, the unit is 75 protected against dust and the elements and thereby maintained clean and efficient.

Furthermore, by the provision of light colored gaskets the illuminating efficiency of 80 the unit is considerably greater than would otherwise be the case.

While I have illustrated my invention in connection with a special form of construction, it will be understood that in view of the disclosure those versed in the art may 85 readily vary the details without departing from the spirit of the invention or from the scope of the claims herein.

What I claim as new and desire to secure by Letters Patent of the United 90 States is:—

1. A lantern having a top frame and a bottom frame and a series of ribs interposed between the top and the bottom frames, said elements forming a series of panel frames, a glass panel for each frame, a non-metallic gasket imbedded in each rib for protecting the glass from the metal, each of said ribs serving as a frame element for two adjacent panels, the gasket on each rib protruding between the two adjacent panels to prevent the panels from coming into contact. 100

2. A lantern having a top frame and a bottom frame and a series of ribs interposed between the top and the bottom frames, said elements forming a series of panel frames, a glass panel for each frame, a non-metallic gasket for each rib for protecting the glass from the metal, each of said ribs serving as a frame element for two adjacent panels, the gasket for each rib protruding between the two adjacent panels for preventing the panels from coming into contact. 110

3. A lantern having a top frame and a bottom frame and a series of ribs interposed between the top and bottom frames said elements forming a series of panel frames, a glass panel for each frame, a non-metallic gasket for each rib for protecting the glass from the metal, each of said ribs serving as 115 a frame element for two adjacent panels, the gasket for each rib protruding between the two adjacent panels for preventing the panels from coming into contact, said gasket being of light colored material. 120

In witness whereof, I have hereunto set my hand this 28th day of February, 1925.

JOSEPH W. GOSLING.
